WHEEL COVER

Jack N. Humbert, Birmingham, Mich., assignor to General Motors Corporation, Detroit, Mich., a corporation of Delaware

Filed June 21, 1961, Ser. No. 65,672

Term of patent 7 years

(Cl. D14—30)

I claim:

The ornamental design for a wheel cover, substantially as shown.
